UNITED STATES PATENT OFFICE.

HENRY J. BECK AND LAWRENCE M. RAKESTRAW, OF TOLEDO, OHIO, ASSIGNEES TO THE UNITED ENGINEERING COMPANY, OF TOLEDO, OHIO, A CORPORATION OF OHIO.

MULTIPLE-FACE FINISHER.

1,205,696.

Specification of Letters Patent. Patented Nov. 21, 1916.

Application filed July 6, 1914. Serial No. 849,035.

To all whom it may concern:

Be it known that we, HENRY J. BECK and LAWRENCE M. RAKESTRAW, citizens of the United States, residing at Toledo, Lucas county, Ohio, have invented new and useful 5 Multiple-Face Finishers, of which the following is a specification.

This invention relates to mechanism for forming or finishing surfaces of articles. 10 This invention has utility when embodied in mechanism for grinding, buffing and polishing polygonal faced articles, as bolts, nuts, bushings, etc., having particular adaptation in connection with spark plug bushings. 15

Referring to the drawings: Figure 1 is a side elevation of an embodiment of the invention for dressing and finishing hexagonal faces of a spark plug bushing; Fig. 2 is a fragmentary view on a larger scale showing features of the clamping means or article locking device; Fig. 3 is a view of the opposite side of the machine from the showing in Fig. 1; Fig. 4 is an end 20 view of the machine; Fig. 5 is a fragmentary side elevation of the machine on the opposite side from the showing in Fig. 2; Fig. 6 is a view of the structure in Fig. 5, looking from the right toward said figure; Fig. 7 is a fragmentary view of the device of Fig. 6, additional structure being broken away; and Fig. 8 is a fragmentary sectional view on the line VIII—VIII, Fig. 7, looking in the direction of the arrow. 25

Mounted on the frame 1 are the bearing brackets 2, 3, (Fig. 4) carrying the shaft 4. This shaft 4 has on one end thereof the loose pulley 5 from which the driving belt may be shifted to the fast pulley 6 to drive 30 the shaft 4. This shaft 4 intermediate the bearing brackets 2, 3, has the eccentric section 7 (Fig. 6) with which may engage the set screw 8 to lock the rotary carrier or disk member 9 to the shaft 4. The eccentricity 35 of the opening in the disk or carrier 9 is equal to the eccentricity of the shaft section 7 so that when the set screw 8 locks this disk 9 with its eccentricity opposite to the eccentricity of the shaft section 7, the carrier 9 will rotate concentric with the shaft 4. Departures in the adjustment from this 40 relation will introduce additional or eccentric travel in the rotation of the carrier as driven by the shaft 4. This carrier 9 has 50 in its periphery fixed seats 10 opposed to

which are the adjustable seats 11 having the slots 12 with which screws 13 may engage to lock the adjustable seat elements 11 in sliding position for movement toward and from the opposing seat 10 to lock, in this instance, a hexagonal article or spark plug bushing 14 in position therebetween. This locking is accomplished automatically. The seat element 11 has recess 15 therein engaged by the head 16 (Fig. 2) of the lever 17 which has the spring 18 normally holding the element 11 away from the opposing seat 10 or in releasing position as to the article.

Mounted on the fulcrum 19 for the lever 17 is the arm 20 between which arm 20 and the end of the lever 17 away from its head 16 coacts the spring 21. When this spring 21 is compressed, it is effective to overcome the action of the spring 18 and rock the lever 17 so that its head 16 will force the element 11 to yieldably lock the article 14 between the faces 10, 11. To automatically accomplish this locking action, a cam 21' is provided for each of the arms 20. These 70 cams 21', or eccentrics, are mounted on the pins 22 which carry arms 23, 24. Mounted on the extension 25 from the bearing 3 is the cross arm 26 carrying pins 27, 28, which 75 serve in the rotation of the carrier 9 to automatically lock and release the articles 80 14 in the carrier 9.

Referring to Fig. 3: As the arms 24 travel past the pin 28, the pins 24 are locked toward the stops 28' to shift the cams 21' into 85 position to throw the arms 20 for locking the elements in the carrier during the downward travel of the carrier. As the articles approach the top of the carrier, from this carrier rotation, the pins 27 strike the arms 23 to move toward the opposite side of stops 28' to that engaged by the pins 24 and reverse the rocking of the cams 21' to release or unlock the articles disposed between the seats 10, 11. Accordingly as the articles 90 are carried down one side, across the bottom and up the other side of the machine by the carrier, they are firmly locked in position. During this travel of the articles 95 means are provided for acting upon the articles, in this instance to finish opposite faces of the polygons of the bushings. This action is simultaneous in dressing and finishing the opposite faces of each article as the articles pass between the wheels 29 100 105 110

mounted on the shafts 30 carried in the bearings 31 rockably mounted on the bracket studs 32. The intermediate brackets 33 (Fig. 4) carrying the screws 34 having the 5 adjusting wheels 35, 36 thereon permit such 10 gaging of the inward limit of movement for these wheels as well as the give therebetween in the resiliency of the springs 37 mounted on said screw shafts 34. These 15 wheels 29 are driven by the pulleys 38 at a high speed of rotation and in the direction which will force the articles against the fixed seat 10 as they rub the exposed faces of the articles for grinding, buffing or polishing, as the surface of the wheels may be 20 equipped to perform. The variation in the eccentricity of the rotary carrier and its shaft mounting introduces the travel across the face of these rotary members so that the 25 wearing of these wheels may be uniform throughout their extent.

In operating the machine with the wheels disposed to finish the desired exposed faces, in this instance laterally arranged as to the 25 carrier, the articles are supplied between the cheeks 39 (Figs. 5, 7) and the locking of the articles at once occurs through the automatic devices described for shifting the seat element 11. There may be polishing of any 30 exposed surface of the held article say when in a peripheral position as to the carrier instead of lateral position as to the carrier as herein shown. The peripheral embodiment is especially desirable in connection 35 with hexagonal elements or other elements having lateral as well as terminal faces to be finished, which finishing of the terminal faces might occur simultaneously with the 40 finishing of the lateral faces.

In the instance of hexagonal articles, the travel in one rotation of the carrier will simultaneously finish two opposing faces of the article. This leaves two other pairs of faces for finishing. In the machine of this 45 disclosure, these additional faces may be finished automatically by the machine itself changing the position of the article to expose successive pairs of the opposing faces in succeeding rotations of the carrier.

Adjacent the position of each clamp or pair of holding seats, the carrier 9 has a pin 40 disposed to contact the arm 41 of the vertically disposed rock shaft 42 (Figs. 5, 47, 8). This shaft 42 is mounted in a bracket 55 48 adjustably positioned by the bolt 44 and the arm 45 as to the eccentric 7 of the shaft 4. This arm 45 is loosely mounted on the shaft section 7 and is held from rotation (Fig. 1) by the stem 46 upwardly extending 60 to engage in the socket or sleeve 47 remote from the machine. This sleeve permits the carrier to have the radial variations of positions caused by the eccentric shaft 7 and still maintains the bracket 43 in the desired vertical position.

The rock shaft 42 is normally held with its arm 41 in the direction of the projecting pins 40 by the torsion spring 48. When the pin 40 strikes the arm 41 and rocks the shaft 42 against the resistance of the torsion spring 48, it causes the shaft 42 to carry with it the arm 49 having the yielding face 50, say of rubber, to contact the article 14 which has been released and is still resting between the opposing seats 10, 11, and rotates such article a sufficient distance to expose another pair of faces outside the clamping device. Opposing the arm 49 is the plunger 51 actuated by the spring 52 to have its yielding face 50 grip the opposite side of the article 14 and assist the arm 49 in the rotation of the article. The nuts 53 permit such adjustment of this plunger 51 as may be desired in practice.

In the treating of six sided articles two 85 shiftings after the initial placing completes the finishing of the three pairs of faces and the article thus dressed is ready for removal from the machine. This is automatically accomplished by the star wheel 54 mounted on the bracket 55 extending laterally of the U-bracket 43. The pin 55' on the face of the carrier 9 is in such position that it will rotate the star wheel 54 one arm's distance in each rotation of the carrier 9. As the 90 shifting occurs between the first and second and between the second and third rotations, two arms of the star wheel 54 are blank between the pins 56 carried by two of the arms of this star wheel. These pins 56 are in position to act upon the arm 57 pivoted to the bracket 55 and thereby pull such arm 57 toward the axis of the wheel 54 causing the flexible member 58 connected to the pin 59 on the shaft 60 to draw said pin 59 into the 100 upright or full line position shown in Fig. 5. This rocking of the shaft 60 carries the arm 61 thereof upward to render taut the spring 62 extending to the hammer arm 63 and in angular relation thereto is the arm 64 having the link 65 connected to the cam shoe 70 pivoted on the shaft carrying the star wheel 54.

In the travel of the carrier 9, the pins 40, which contact the rock shaft 42, also contact the cam 70 and in lifting said cam draw the hammer 63 inward or toward the center of the carrier 9, and with the spring 62 taut, the passing of the pin 40 by the cam 70 quickly releases this hammer 63 which 115 strikes a side of the released article 14 and throws it out of the carrier 9. This action occurs with each of the articles passing during the complete rotation of the carrier 9 when the pin 71 on the carrier engages the lever 72 and rocks said lever into the dotted line position shown in Fig. 5, thereby taking the tension off the spring 62. In the passing 120 of the next two rotations which correspond with the arms of the star wheel 54 which do 130

not carry pins 56, the pins 40 of the carrier acting upon the cam 70 slightly rock the hammer 63 and as there is no spring action by spring 62, this hammer does not come in contact with an article for discharging such article. After two shifting rotations, the next pin on the star wheel comes into play for a resetting of the discharge mechanism during the complete rotation of the carrier. The carrier may be charged simultaneously with the discharge of the articles therefrom so that the device is one possible of handling a maximum quantity of work with great rapidity and performing such work in a satisfactory manner most economically.

What is claimed and it is desired to secure by Letters Patent is:

1. A machine for multiple faced articles embodying a rotary holder for an article, said holder providing a radially open pocket having automatic engaging means including a radially fixed seat and an opposing relatively movable seat.
2. A machine for multiple faced articles embodying a rotary holder for an article, said holder having automatic engaging means including seats, and lever actuating means for a seat to article holding position.
3. A machine for acting upon multiple faced articles embodying a rotary holder for an article, said holder having automatic engaging means including seats, a seat actuating lever, and a yieldable arm for shifting the lever.
4. A machine for acting upon multiple faced articles embodying a rotary holder for an article, said holder having engaging means including a seat, and actuating mechanism for the seat including a rocking cam.
5. A machine for acting upon multiple faced articles embodying a rotary holder for an article, and automatic means for bringing the holder into closed and open positions for locking or releasing an article therein including a lever, an eccentric, and an arm actuated by the eccentric to shift the lever.
6. A machine embodying a revolving holder, and rubber buffer means for shifting an article in said holder.
7. A machine embodying a holder for an article against rotation, releasing means coacting with the holder, and yieldable article engaging buffer means for shifting the released article in the holder.
8. A machine embodying a holder for an

article against rotation, releasing means coacting with the holder, stationary article engaging means for shifting the released article, and resetting means for locking the article in the holder.

9. A machine embodying a holder for an article against relative movement, releasing means coacting with the holder, article engaging means for rotating the released article in the holder, and resetting means for locking the article in the holder.

10. A machine embodying a revolving holder, and a discharge device including a hammer and a spring for actuating the hammer for removing articles from the holder.

11. A machine embodying a holder for an article against relative movement, releasing means coacting with the holder to free an article in the holder, and a recoil discharge device for removing a freed article from the holder.

12. A revolving article holder, a rotary member disposed for acting upon a held article, and means in addition to the revolution of the holder and rotation of the member relatively moving the holder and member to distribute the action of the member on the article.

13. A finisher for polygonal faced articles embodying a rotary support for the articles in annular series, retaining means for holding the articles in the support with opposite faces exposed, stationary wheels for simultaneously acting upon said opposite exposed faces of the articles, and eccentric means for shifting the support as to the wheels.

14. A plurality of opposing surface-forming means for articles, and a rotary support disposed therebetween embodying article receiving seats for exposing articles held therein, said seats including a movable member, a lever for shifting said member, a spring for actuating said lever to move the member toward article freeing position, an opposing spring for maintaining the seat member in article holding position, an arm for compressing the opposing spring, and an eccentric for actuating the arm to effect shifting of the seat member.

In testimony whereof we affix our signatures in the presence of two witnesses.

HENRY J. BECK.

LAWRENCE M. RAKESTRAW.
